UNITED STATES PATENT OFFICE

JOHN P. NORTHEY, OF TORONTO, ONTARIO, CANADA

SOUND-PRODUCING DEVICE

Application filed March 1, 1929, Serial No. 343,817. Renewed August 21, 1930.

This invention relates to sound producing devices of the type shown in my prior Patent No. 736,428 in which high pressure air was used to vibrate a hollow piston in a cylinder having orifices in its wall, the piston also having orifices which, by the vibration of the piston, are alternately brought into and out of alignment with the orifices of the cylinder, thus controlling the flow of low pressure air to cause a rapid succession of puffs of air to produce a musical note. As the driving of the piston requires air at high pressure, a somewhat expensive air compressing and cooling system has heretofore been necessary to provide and store such air, and the object of the present invention is to so construct the device that air at a materially lower pressure may be employed to actuate the piston.

In the prior constructions the hollow piston was provided with an enlarged head operating in a separate chamber or cylinder of greater diameter than that of the sound producing cylinder and the control of the driving air was effected solely by ports in the enlarged piston head and its cylinder wall. The air passages were thus of necessity of small cross sectional area relative to their length so that frictional losses in the air were high and lag in transmission so great that high air pressures were essential.

In the present invention I have provided a construction in which the hollow piston and its cylinder share in the control of the driving air to provide supplemental and more direct exhaust from behind the piston head, and also to provide supplemental air passages from the inlet to the back of the piston head.

The invention is hereinafter more specifically described and is illustrated in the accompanying drawings in which

Fig. 1 is a longitudinal section of the apparatus;

Fig. 2 an enlarged sectional detail of parts of the apparatus showing the piston in the exhaust position;

Fig. 3 a similar view showing the piston in the intake position; and

Fig. 4 a detail in cross section on the line 50 4-4 in Fig. 1.

In the drawings like numerals of reference indicate corresponding parts in the different figures.

1 is the casing in which is mounted a cylindrical sleeve 2. The wall of this cylinder has a series of sound producing orifices 3 formed therein, which will usually be spaced at equal distances apart. Within the cylinder a hollow piston 4 is adapted to reciprocate, this piston being also provided with sound producing orifices 5 adapted to be brought into alignment with the orifices in the cylinder by the reciprocation of the piston.

The piston is provided with an enlarged head 6 adapted to reciprocate in the cylinder enlargement 7. The apertured part of the piston is separated from the remainder of the piston by the diaphragm 8. The open end of the piston communicates with the horn 9, which is suitably secured to the end of the casing.

Within the casing is formed the chamber 10 communicating with the air inlet 11. The sound is produced by the reciprocation of the piston, which causes its sound producing orifices to coincide at regular intervals with the orifices of the cylinder 2, thus producing a series of puffs of air which occur at such intervals as to form a musical note.

The piston and casing are constructed in the following manner to effect the reciprocation of the piston. The cylinder enlargement 7 is provided with the annular ports 12, 13, which are connected by a plurality of longitudinal passages 25. In the wall of the cylinder enlargement is also formed an annular port 14 with which communicate a plurality of radial passages 15 which communicate with an annular chamber 16 formed in the casing 1. With this chamber communicates the air inlet 17. Intermediate the ports 12, 13 is an annular exhaust port 18 with which communicate a plurality of radial passages 19 which communicate with an annular chamber 20 formed between the casing and the cylinder enlargement and communicating with the radial exhaust passages 21 between the head 22 and the casing. The piston head has an annular groove 23 formed

in its exterior surface, which is so positioned that, when it forms a communication between the exhaust port 18 and the port 13, the port 12 is uncovered. Also through the head of the piston are formed a plurality of passages 24 opening through the forward face of the piston head and through its periphery. Preferably the inner parts of these passages are formed by an annular groove in the exterior surface of the piston head.

From this construction it follows that, when the parts are in the position shown in Fig. 2, air from behind the piston head is exhausted through the port 12, the longitudinal passages 25, the port 13, the groove 23, the exhaust port 18, the passages 19, the chamber 20 and the passages 21. The momentum of the piston then carries it a little further to the right. There is then the condition that air under pressure is acting on the front of the piston while the pressure has been exhausted from behind. The piston is then forced to the position shown in Fig. 3 in which the groove 23 no longer forms a communication between the port 13 and the exhaust port 18. In this position the port 12 is still open to the space behind the piston head while the passages 24 provide a passage for air from the space in front of the piston head through the port 13, passages 25 and port 12 to the space behind the piston head. The same air pressure then exists both in front of and behind the piston head, but, owing to the greater surface of the piston head exposed to air pressure at the back than at the front, the excess pressure drives the piston forward to and beyond the exhaust position previously described. The piston is thus reciprocated to effect sound production as hereinbefore described.

The parts previously described are old in the art, but to them I have now added the following features of construction to give a supplemental exhaust and air admission for the driving of the piston. In the cylinder wall I form an annular supplemental exhaust port 26 with which communicate a series of radial passages 27 communicating with extensions 25^a of the longitudinal passages 25. A supplemental exhaust port 28 is formed in the piston wall. This is preferably so positioned that it comes into alignment with the supplemental exhaust port 26 at or about the time the exhaust port 18 is opened to the space behind the piston head by means of the groove 23. Thus part of the exhaust takes place directly from the passages 25 through the extensions 25^a, the radial passages 27 and the ports 26 and 28 to the interior of the hollow piston where it mingles with the exhaust air passing inwardly through the orifices 5. A supplemental path for air under pressure is provided through the medium of the supplemental inlet port 29 formed in the cylinder wall and the groove 30 formed in the outer

surface of the piston. This groove is of such a width that it forms a communication between the supplemental inlet port 29 and the space in front of the front wall of the piston head. The annular supplemental port is connected by longitudinal passages 31 with the radial passages 27 so that the supplemental driving air passes from the space aforesaid through the groove 30, passages 31, passages 27, the extensions 25^a, the longitudinal passages 25, 75 and the port 12 to the space behind the piston head. I find that, with the new construction, driving air at a lower pressure may be employed, thus not only effecting economies in operation but also in the expense of installation.

What I claim as my invention is:

1. A sound producing device comprising a cylinder having sound producing orifices in its wall; a hollow piston adapted to reciprocate in said cylinder, open at one end and having sound producing orifices in its wall adapted to be brought into alignment with the orifices in the cylinder by the reciprocation of the piston; an enlarged head at the end of the piston remote from its open end; an enlargement of the cylinder in which the piston head reciprocates; an air inlet and an air outlet in said enlargement; ports in the piston head and the wall of the cylinder enlargement controlling the admission and exhaust of the piston driving air; an exhaust port in the wall of the hollow piston forming a supplemental air outlet; an exhaust port in the cylinder with which the piston port may register; and a passage in the cylinder walls forming a communication between the last mentioned port and an exhaust passage of the cylinder enlargement.

2. A sound producing device comprising a cylinder having sound producing orifices in its wall; a hollow piston adapted to reciprocate in said cylinder, open at one end and having sound producing orifices in its wall adapted to be brought into alignment with the orifices in the cylinder by the reciprocation of the piston; an enlarged head at the end of the piston remote from its open end; an enlargement of the cylinder in which the piston head reciprocates; ports in the piston head and the wall of the cylinder enlargement controlling the admission and exhaust of the piston driving air; an exhaust port in the wall of the hollow piston; an exhaust port in the cylinder with which the piston port may register; a passage in the cylinder walls forming a communication between the last mentioned port and an exhaust passage of the cylinder enlargement; an air admission port in the cylinder wall communicating with an air admission passage leading to the back of the piston head; and a groove in the piston wall adapted, when air is being admitted behind the piston head to form a communication between the said port and the space in

front of the piston head, said space being in constant communication with an air supply port.

3. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; ports in the piston head and the wall of the cylinder enlargement controlling the admission and exhaust of the piston driving air; and co-operating ports in the cylinder and piston walls forming an exhaust supplemental to that of the piston head and the cylinder enlargement.

4. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; ports in the piston head and the wall of the cylinder enlargement controlling the admission and exhaust of the piston driving air; co-operating ports in the cylinder and piston walls forming an exhaust supplemental to that of the piston head and the cylinder enlargement; and co-operating ports in the cylinder and piston walls forming air admission means supplemental to that of the piston head and the cylinder enlargement.

5. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; an air port in the wall of the cylinder enlargement whereby the space between the annular walls of the piston head and cylinder enlargement is constantly in communication with air under pressure; an exhaust port opening through the cylindrical wall of the cylinder enlargement; two ports opening through said wall, one at each side of the exhaust port; a passage in the wall connecting said ports; a groove in the piston head adapted to form a communication between the forward one of said ports and the exhaust port; a passage in the piston head opening through its forward end and through its wall forward of said groove, the groove and passage being so positioned that, when the passage forms a communication between the forward port and the annular space in front of the piston head thus admitting air pressure behind the piston head, the exhaust port is cut off and when the groove is forming a communication between the forward port and the exhaust port, the passage is out of alinement with the former; a supplemental passage extending from the wall passage hereinbefore mentioned and terminating in a supplemental exhaust port in the cylinder wall; a port in the piston wall adapted to aline with said supplemental exhaust port at or about the time the main exhaust port in the cylinder enlargement is functioning; a supplemental inlet port in the cylinder wall communicating with the supplemental passage aforesaid; and a groove formed in the piston wall adapted to form a communication between said

the piston head opening through its forward end and through its wall forward of said groove, the groove and passage being so positioned that, when the passage forms a communication between the forward port and the annular space in front of the piston head thus admitting air pressure behind the piston head, the exhaust port is cut off and when the groove is forming a communication between the forward port and the exhaust port, the passage is out of alinement with the former; a supplemental passage extending from the wall passage hereinbefore mentioned and terminating in a supplemental exhaust port in the cylinder wall; and a port in the piston wall adapted to aline with said supplemental exhaust port at or about the time the main exhaust port in the cylinder enlargement is functioning.

6. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; an air port in the wall of the cylinder enlargement whereby the space between the annular walls of the piston head and cylinder enlargement is constantly in communication with air under pressure; an exhaust port opening through the cylindrical wall of the cylinder enlargement; two ports opening through said wall, one at each side of the exhaust port; a passage in the wall connecting said ports; a groove in the piston head adapted to form a communication between the forward one of said ports and the exhaust port; a passage in the piston head opening through its forward end and through its wall forward of said groove, the groove and passage being so positioned that, when the passage forms a communication between the forward port and the annular space in front of the piston head thus admitting air pressure behind the piston head, the exhaust port is cut off and when the groove is forming a communication between the forward port and the exhaust port, the passage is out of alinement with the former; a supplemental passage extending from the wall passage hereinbefore mentioned and terminating in a supplemental exhaust port in the cylinder wall; a port in the piston wall adapted to aline with said supplemental exhaust port at or about the time the main exhaust port in the cylinder enlargement is functioning.

7. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; an air port in the wall of the cylinder enlargement whereby the space between the annular walls of the piston head and cylinder enlargement is constantly in communication with air under pressure; an exhaust port opening through the cylindrical wall of the cylinder enlargement; two ports opening through said wall, one at each side of the exhaust port; a passage in the wall connecting said ports; a groove in the piston head adapted to form a communication between the forward one of said ports and the exhaust port; a passage in the piston head opening through its forward end and through its wall forward of said groove, the groove and passage being so positioned that, when the passage forms a communication between the forward port and the annular space in front of the piston head thus admitting air pressure behind the piston head, the exhaust port is cut off and when the groove is forming a communication between the forward port and the exhaust port, the passage is out of alinement with the former; a supplemental passage extending from the wall passage hereinbefore mentioned and terminating in a supplemental exhaust port in the cylinder wall; a port in the piston wall adapted to aline with said supplemental exhaust port at or about the time the main exhaust port in the cylinder enlargement is functioning; a supplemental inlet port in the cylinder wall communicating with the supplemental passage aforesaid; and a groove formed in the piston wall adapted to form a communication between said

supplemental inlet port and the annular space in front of the piston head when air is being admitted behind the piston.

7. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; means for supplying air under pressure to and exhausting it directly from the cylinder enlargement to effect the reciprocation of the piston; means for supplying air under pressure to the exterior of the cylinder to effect sound production; and supplemental means for effecting exhaust of the piston driving air to the interior of the hollow piston to mix with the exhaust sound producing air.

8. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; means for supplying air under pressure to and exhausting it directly from the cylinder enlargement to effect the reciprocation of the piston; means for supplying air under pressure to the exterior of the cylinder to effect sound production; supplemental means for effecting exhaust of the piston driving air to the interior of the hollow piston to mix with the exhaust sound producing air; and means controlled by the body of the piston for providing an additional air channel between the driving air supply and the cylinder enlargement behind the piston.

9. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; ports in the piston head and the wall of the cylinder enlargement controlling the admission and exhaust of the piston driving air; an air admission port in the cylinder wall communicating with an air admission passage leading to the back of the piston head; and a groove in the piston wall adapted, when air is being admitted be-

hind the piston head to form a communication between the said port and the space in front of the piston head, said space being in constant communication with an air supply port.

10. A sound producing device comprising a cylinder having sound producing orifices in its wall; a hollow piston adapted to reciprocate in said cylinder, open at the end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; ports in the piston head and the wall of the cylinder enlargement controlling the admission and exhaust of the piston driving air; and co-operating ports in the cylinder and piston walls forming air admission means supplemental to that of the piston head and the cylinder enlargement.

11. A sound producing device comprising a cylinder having sound producing orifices in its wall; a hollow piston adapted to reciprocate in said cylinder, open at one end and having sound producing orifices in its wall adapted to be brought into alinement with the orifices in the cylinder by the reciprocation of the piston; an enlarged head at the end of the piston remote from its open end; an enlargement of the cylinder in which the piston head reciprocates; means for supplying air under pressure to and exhausting it directly from the cylinder enlargement to effect the reciprocation of the piston; means for supplying air under pressure to the exterior of the cylinder to effect sound production; and means controlled by the body of the piston for providing an additional air channel between the driving air supply and the cylinder enlargement behind the piston.
